INSIDE RING ENGRAVING ATTACHMENT

Wilbur M. Garing, Torrington, Wyo.

Application November 1, 1950, Serial No. 193,497

4 Claims. (Cl. 90—61)

1

This invention relates to engraving machines of the pantograph type used primarily for engraving jewelry and the like, and in particular a V-jaw holder for a ring and an L-shaped stylus holder with a clamp for attaching the holder to a following arm of a pantograph unit whereby the stylus or diamond point extends inside of a ring and is actuated by a tracing point of the pantograph.

The purpose of this invention is to provide means for engraving names, dates, initials, and the like inside of rings by mechanically actuated instrumentalities.

Various duplicating devices have been provided of the pantograph type for drawings, cutting, and engraving and whereas the devices work satisfactorily on the surface they are not adapted for use on the inside of an object, such as engraving the inside of a ring. With this thought in mind this invention contemplates an attachment for engraving machines whereby a diamond cutter is suspended by an L-shaped holder mounted on a pantograph whereby with a tracing stylus following characters on a work board or dial the diamond point duplicates the characters on the inner surface of a ring.

The object of this invention is, therefore, to provide means for forming mounting attachments on engraving machines whereby with a ring vertically positioned on the bed of the machine a diamond point actuated by a tracing stylus enters the ring and engraves the inner surface thereof.

Another object of the invention is to provide means for rigidly clamping a ring to facilitate engraving on the inner surface.

Another object of the invention is to provide a master disc having letters, numerals or characters thereon and means for mounting the disc on the work board of an engraving machine.

A further object of the invention is to provide attachments to facilitate engraving the inner surfaces of rings with engraving machines of the pantograph type, which are of a simple and economical construction.

With these and other objects and advantages in view the invention embodies a diamond point holder formed with an L-shaped arm having a clamp at the upper end for securing the holder on the spindle housing of a pantograph attachment of an engraving machine, V-shaped gripping jaws for rigidly holding a ring on the machine, and a master wheel having characters thereon positioned to be followed by a stylus point of the pantograph attachment.

2

Other features and advantages of the invention will appear from the following description taken in connection with the drawings wherein:

Figure 1 is a plan view of an engraving machine having a pantograph attachment showing the position of the ring holding gripping jaws, the diamond point holder, and the master disc.

Figure 2 is a plan view illustrating the master disc with the mounting elements therefor.

Figure 3 is a longitudinal section through the master disc and mounting elements taken on line 3—3 of Figure 2.

Figure 4 is a detail showing an end elevational view of the master disc with the disc retaining dogs and clamping means for the dogs.

Figure 5 is a plan view of the mounting plate for the master disc with the disc and holding elements therefor omitted.

Figure 6 is a detail showing a plan view of the dog.

Figure 7 is a detail showing an end elevational view of the disc retaining dog and clamping nut therefor.

Figure 8 is a detail illustrating the V-shaped gripping jaws for holding a ring in position on the bed of the engraving machine.

Figure 9 is a detail showing a plan view of one of the gripping jaws shown in Figure 8.

Figure 10 is an end elevational view looking toward the V-shaped ring gripping surface of one of the gripping jaws.

Figure 11 is a longitudinal section through one of the ring gripping jaws taken on line 11—11 of Figure 10.

Figure 12 is a side elevational view illustrating the diamond cutter holder that is attached to the spindle housing of the pantograph.

Figure 13 is a plan view of the holder shown in Figure 12.

Figure 14 is an end elevational view of the holder shown in Figure 12.

Figure 15 is a detail on an enlarged scale illustrating the diamond cutter mounting means in the end of the arm at the lower end of the holder with the upper part of the arm broken away and with the outer end of the arm broken away and shown in section.

Referring now to the drawings wherein like reference characters denote corresponding parts the engraving machine attachment for engraving the inside of rings of this invention includes an L-shaped holder 10, V-shaped gripping jaws 11 and 12 and a master disc 13 which is rotatably mounted on a pin 14 of a mounting plate 15 and which is retained in operative position by

a dog 16, a point 17 of which snaps into notches 18 in the periphery of the disc 13.

The holder 10 is provided with a horizontally disposed lower arm 19 and a diamond point 20 in a holder 21 is carried by a bushing 22 that is threaded in a socket 23 in the outer end of the arm. The bushing 22 is provided with a screw driver slot 24 and by this means the position of the diamond cutter or point is vertically adjustable.

The upper end of the holder 10 is provided with a clamp 25 which is split on the side opposite to that from which the holder extends and the split side is provided with flanges 26 and 27. A thumb screw 28 extends through an opening 29 in the flange 27 and is threaded in a opening 30 in the flange 26 so that the clamp, which is provided with an internally threaded opening 31 may be threaded on the lower end of a spindle housing 32 of a pantograph arm 33, and clamped in position by the thumb screw 28.

With the holder mounted on the pantograph in this manner the diamond cutter is positioned to enter the ring as indicated by the dotted lines 34 in Figure 8, the ring being clamped between the V-shaped surfaces 35 and 36 of the gripping jaws 11 and 12, respectively.

The jaw 11 is mounted by steel pins 37 and 38 on a traveling block 39 of the work holder 40 of the engraving machine and the jaw 12 is positioned on pins 42 on a similar traveling block 43. The blocks 39 and 43 are actuated by a screw 44 of the machine whereby the V-shaped gripping surfaces are actuated to clamping position with the ring and also moved away from the ring.

As illustrated in Figures 9, 10 and 11, the V-shaped surfaces 35 and 36 are formed in sections 45 and 46 of the jaws 11 and 12 and the inner faces of the V-shaped surfaces are provided with V-shaped recesses as indicated by the numerals 47 and 48 in Figures 10 and 11. These recesses extend outwardly from points 49 and 50 and are substantially triangular shaped in section.

The ring gripping jaws 11 and 12 are substantially L-shaped in elevation, as illustrated in Figure 11, the jaw 11 being provided with an upper flat section 51 having a slot 52 therein, and the jaw 12 having a similar section 53 with a slot 54 therein. With the jaws shaped in this manner they are readily positioned on the traveling blocks 39 and 43, as illustrated in Figure 8.

The master disc 13, as illustrated in Figures 2, 3 and 4 is provided with an outer row of letters 55 and an inner row of numerals 56. The disc is formed with a threaded centrally positioned opening 57 and a threaded neck 58 of a cup shaped washer 59 in which a knurled head 60 of the pin 14 is positioned, is threaded in the opening with the pin extending through a centrally positioned opening 61 of the cup shaped washer and threaded into an opening 62 in the mounting plate 15. The knurled head 60 is provided with a screw driver slot 63 by which the friction of the master disc may be adjusted.

The dog 16 is provided with a key 64 that is slidably mounted in a slot 65 in the mounting plate 15 and a spring 66, also positioned in the slot 65 urges the point 17 of the dog toward the master disc 13 and holds the point in one of the notches 18. The dog 16 is also provided with a gripping head 67 by which it may be manually withdrawn from the notches of the master disc. The key 64 is provided with a threaded stud 68 on which a flat nut 69 is threaded to retain

the dog in position on the upper surface of the plate 15.

The mounting plate 15 is provided with beveled edges 70 and 71 to correspond with longitudinally disposed grooves 72 and 73 in the work board 14 of the engraving machine. A threaded stud 75 having a head 76 extends through the mounting plate 15, being threaded in an opening 77 in the plate and extending into a threaded opening in the work board of the machine.

With the parts arranged in this manner a ring, as indicated by the numeral 34 is clamped in the V-shaped gripping jaws by turning the screw 44 and with a letter that it is desired to engrave in the inner surface of the ring, on the master disc 13, in the proper position the tracing stylus is carried over the lines of the letter whereby the diamond cutter 20, which follows the stylus, engravés the letter on the inner surface of the ring. By manually indexing the ring to obtain the proper spacing between letters one letter, or figure, after another may be engraved in the inner surface of the ring by rotating the master disc 13 and actuating the tracing stylus over the letter or figure.

The parts of the pantograph may be adjusted so that the cutter in the end of the arm 19 of the holder 10 extends into the ring and the mounting plate 15 of the master disc 13 may be set according to the ring and the letters to be engraved therein to a predetermined position on the work board of the engraving machine. In order to facilitate setting the master disc the mounting plate may be provided with a setting point 79 that is positioned to register with an indexing point 80 on the work board of the machine.

As illustrated in Figure 1 the pantograph parts are suspended from a mounting bar 81 by pins 82 and 83 and the bar 81 is adjustably mounted on a bracket 84 on the bed of the machine by a pin 85, the position of which may be adjusted by an adjusting screw 86. By this means the positions of the cutting point and tracing stylus may readily be adjusted to engrave initials, names, dates and the like on the inner surfaces of rings, or other jewelry, and the outer surfaces of foot balls, basketballs, cigarette lighters and the like may be similarly engraved.

It will be understood that modifications may be made in the design and arrangement of the parts without departing from the spirit of the invention.

What is claimed is:

1. A ring engaging clamp, for use with the travelling blocks of a work holder of an engraving machine, comprising a pair of substantially L-shaped jaws that are mounted on the travelling blocks, V-shaped surfaces mounted on said jaws in vertical relation thereto, and V-shaped recesses formed in the inner faces of said V-shaped surfaces whereby a ring may be gripped by said jaws when positioned in said V-shaped recesses.

2. A ring engraving clamp as in claim 1 wherein means is provided for urging the L-shaped jaws toward each other to engage and retain the ring in the said V-shaped recesses.

3. A ring engaging clamp as in claim 1 wherein said L-shaped jaws are provided with elongated slots for mounting said jaws on the travelling blocks of the engraving machine.

4. A ring engaging clamp as in claim 1 wherein the V-shaped surfaces of the L-shaped jaws converge inwardly toward the center of the jaws and the V-shaped notches extend in said surfaces

at right angles thereto and also converge toward the center of the jaws.

WILBUR M. GARING.
